UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

BOILER.

Application filed December 23, 1920. Serial No. 432,687.

My invention relates to improvements in heating apparatus, and the same has for its object more particularly to provide a boiler for heating large buildings or structures, 5 which is simple in construction, easy to operate, and efficient in performance.

Further, said invention has for its object to provide a boiler which may be readily enlarged in order to lengthen the path of 10 travel of the hot gases and products of combustion between the combustion chamber and the stack opening.

Further, said invention has for its object to provide a boiler composed of a series of 15 transverse connected sections, arranged side by side, and in which each of said transverse sections combines with the sections of a series arranged end to end whereby the length of the boiler from front to back may be increased or decreased at will, as desired.

Further, said invention has for its object to provide a boiler comprising a plurality of transversely connected elements, certain 20 of which constitute a fuel receptacle, and a combustion chamber, and the remaining elements form alternately ascending and descending flues leading to the stack.

Further, said invention has for its object to provide a boiler having a combustion 25 chamber, formed independently of the fuel receptacle, in which the gases and products of combustion liberated by the fuel are received and mixed with preheated air delivered to said combustion chamber by means of secondary air ducts.

Further, said invention has for its object to provide novel means which are detachably arranged within the combustion chamber for conducting secondary air thereto.

Further objects will in part be obvious, and in part be pointed out hereinafter.

To the attainment of the aforesaid objects and ends my invention consists in the novel details of construction and in the combination, connection and arrangement of parts hereinafter more fully described and then pointed out in the claims.

In the accompanying drawings:

Figure 1 is a front elevation showing one 50 form of boiler constructed according to, and embodying my said invention;

Fig. 2 is a side view;

Fig. 3 is a plan or top view with the enclosing jacket partly broken away;

Fig. 4 is a longitudinal section on the line 55 4—4 of Fig. 3;

Fig. 5 is partly a longitudinal section on the line 5—5 of Fig. 4;

Fig. 6 is a vertical section taken on the line 6—6 of Fig. 4 looking in the direction 60 of the arrow; and

Fig. 7 is a similar view taken on the line 7—7 of Fig. 4.

In said drawings, 10 designates the boiler as a whole which is of the sectional type, and 65 capable of enlargement transversely and longitudinally, i. e., from front to rear. The boiler consists essentially of sets of side members each composed of three hollow water sections 12, 13, 14, and four transverse intermediate members 12^a, 12^b, 13^a, 14^a, each composed of a plurality of hollow water sections connected together and to said end or side sections 12, 13, 14, by nipples 15, 15^a, 32^a, 70 33, 46.

The end or side sections 12, 13, 14 and the intermediate sections 12^a, 13^a, 14^a are enclosed by a metal jacket 16 provided upon its 75 inner sides with insulating lining sections 17 of asbestos or other suitable material.

The front of the boiler is provided with an inclined upper portion 18 having fuel openings therein over which are fitted hinged doors 18^a, and below said inclined portion 18 the front is provided with suitable openings 80 having doors 19, 19^a to permit of access to the burning fuel, and for the removal of ashes from the base of the boiler, and air supply openings controlled by butterfly dampers 19^b.

The sections 12^a of the front transverse member 12 are of less height than the sections 12^b so as to form the inclined opening for the fuel receptacle formed by the members 12^a, 12^b, and the end sections 12.

The front sections 12^a comprise relatively narrow water backed portions 20 from whose opposite sides extend inwardly and downwardly inclined lateral fins 21, the outer edges of which register with those of the adjoining sections and from air inlet openings or passages 22.

Adjacent to their lower ends, the front sections 12^a are each provided with an inwardly and downwardly inclined member 23 which extends about half-way across the fuel receptacle, and co-operates with the bed of ash to support the fuel in position within

- said fuel receptacle. Further, said member 23 serves to prevent the incandescent and the green fuel dropping into the ash pit during the removal of accumulated ash therefrom.
- 5 The sections 12^a are provided at their front portions adjacent to their lower edges with registering eyes 24 to receive a tie rod 25 whose ends extend through the end sections 12, and certain of said sections 12^a are 10 further provided with depending feet 26 in order to support the member 12^a constituting the transverse member 12 as a whole.
- The second transverse member 12^b, which is substantially co-extensive in height with 15 the height of the boiler, is composed of a plurality of hollow water sections 12^b provided along the vertical edges of their uppermost portions with registering ribs 27 which form an unbroken wall portion 28, and below 20 said wall portion the said sections 12^b are reduced in width to form narrow portions 29 from whose opposite sides extend downwardly and forwardly-inclined lateral fins 30, the edges of which register with those of the adjoining sections and form air passages 31 for 25 the hot gases and products of combustion liberated or produced by the burning fuel.
- To the rear of said second member 12^b is arranged the third transverse member 13^a 30 which is composed of a plurality of substantially rectangular sections provided at their forward lower corners with depending portions 32 to receive nipples 32^a whereby said sections may be secured together at their 35 lower ends and to their end sections 13. The upper rear corners of said sections 13^a and the end sections 13 are provided with registering openings to receive nipples 33 whereby the same may be secured together.
- 40 The sections 13^a are provided along their upper edges and at their forward lower edges with oppositely-extending lateral ribs 34 which serve to form a smooth unbroken wall portion 35 having a forwardly projecting portion 36 at its upper end provided with a longitudinal channel or recess 37 to receive the downwardly-extending ribs or projections 38^a formed at the upper rear edges of the secondary air ducts 38.
- 45 Each air duct 38 has an enlarged upper portion 39 forming an air chamber which communicates at its opposite ends with air inlets 40^b provided in the end sections 13, and controlled by rotary valves 41. The 50 vertical edges of said air ducts 38 contact and thus form a wall whose outer surface is directly exposed to the hot gases and products of combustion passing through the combustion chamber 42 formed intermediate the 55 transverse members 12^b and 13^a. The air received by and passing through said ducts is thus preheated before it issues from the open lower ends of said ducts and is mixed with the products of combustion passing 60 through said combustion chamber.

Each air duct section 38 is provided upon its upper side with a pair of upwardly extending lugs 43 having openings therein to receive a hook or other implement when it is desired to remove or replace said duct 70 sections.

The front portions of the sections 13^a above said air ducts 38 are not provided with contacting ribs at their opposite edges in order to leave flue spaces 44 through which 75 the products of combustion may enter, and after passing downwardly between said sections be deflected by the ribs 45 which extend downwardly and forwardly from the upper rear corners of said sections and terminate near the lower central parts of said sections 13^a.

To the rear of said third members 13^a is arranged a transverse rear member which is composed of a plurality of sections 14^a 85 of substantially the same form as the elements 13^a of the preceding member. The front edges of the sections 14^a substantially contact with the rear edges of the sections 13^a in front thereof. 90

The sections 14^a are provided at their upper rear corners and their lower forward corners with nipples 46 whereby said sections may be secured together and to their respective end sections 14. 95

The upper edges of the sections 13^a and 14^a and the corresponding end sections 13, 14, are provided along their upper edges with registering ribs 47, and the rear edges of the sections 14^a and the end sections 14 100 are provided with ribs 48. The sections 14^a and 14 are also provided upon their opposing sides with ribs 49 which extend from the lower forward corners of said sections 14^a, 14 rearwardly and upwardly paralleling the 105 general direction of the ribs 45, and form flue parts 40^a. The said flue parts 40^a form a continuation of the flues 40 formed by the members 13, 13^a. The flues 40, 40^a extend downwardly and communicate with the 110 space provided at the rear of the projection 50 at the lower rearward end of the sections 14^a, which space constitutes a collecting flue 51 connecting said flues 40, 40^a with the smoke outlet 52 provided at the lower 115 rear side of the boiler.

The contacting ribs 47 at the upper edges of the sections 13^a, 14^a are cut away to form openings 53 to permit of the introduction 120 of a tool to clean the flues. These openings are normally closed by removable covers 54, which in turn are concealed by covers 55 provided in the top of the jacket.

The operation of the boiler will be obvious 125 from the foregoing description.

Having thus described my said invention what I claim and desire to secure by Letters Patent is:—

1. A boiler of the character described comprising front, rear and intermediate se- 130

- ries of connected sections forming a fuel receptacle and a combustion chamber, and a series of connected sections constituting the back of the boiler; said series of sections disposed to the rear of the series constituting the front of said combustion chamber forming a series of flues extending from said combustion chamber to the smoke outlet of the boiler, substantially as specified.
10. 2. A boiler of the character described comprising front, rear and intermediate series of connected sections forming a fuel receptacle and a combustion chamber, and a series of connected sections constituting the back of the boiler; said series of sections disposed to the rear of the series constituting the front of said combustion chamber forming a series of flues extending from said combustion chamber to the smoke outlet of the boiler, each of said flues comprising a plurality of parts, certain of which are arranged in one of said series of said sections and the remainder of said parts arranged in other of said series of sections, substantially as specified.
15. 3. A boiler of the character described comprising front, rear and intermediate series of connected sections forming a vertical fuel receptacle and a vertical combustion chamber to the rear of said fuel receptacle, a series of connected sections constituting the back of the boiler, a plurality of flue parts in said back sections, and a plurality of flue parts in the series of sections interposed between the series of sections constituting the front of said combustion chamber and a series of sections constituting the back of the boiler; said last named flue parts cooperating with the flue parts in said back sections to form a series of sinuous flues extending from said combustion chamber to the smoke outlet of the boiler, substantially as specified.
20. 4. A boiler of the character described comprising front, rear and intermediate series of connected sections forming a fuel receptacle and a combustion chamber, a series of connected vertical sections constituting the back of the boiler, and a plurality of laterally-extending registering ribs upon the opposite sides of the sections of said series disposed to the rear of the series constituting the front of said combustion chamber, forming a series of flues intermediate the same extending from said combustion chamber to the smoke outlet of the boiler, substantially as specified.
25. 5. A boiler of the character described comprising front, rear and intermediate series of connected sections forming a fuel receptacle and a combustion chamber, a series of connected sections constituting the back of the boiler and forming flues communicating with the smoke outlet of the boiler; the sections interposed between the series of sections constituting the front of said combustion chamber and the series of sections constituting the back of the boiler, and means arranged in said combustion chamber for conducting secondary air to the base thereof, substantially as specified.
30. 6. A boiler of the character described comprising front, rear and intermediate series of connected sections, forming a fuel receptacle and a combustion chamber, a series of connected sections constituting the back of the boiler and forming flues communicating with the smoke outlet of the boiler; the sections interposed between the series of sections constituting the front of said combustion chamber and the series of sections constituting the back of the boiler, and a plurality of members arranged end to end in said combustion chamber and forming a continuous duct for conducting secondary air to the base of said combustion chamber.
35. 7. A boiler of the character described comprising front, rear and intermediate series of connected sections forming a fuel receptacle and a combustion chamber, a series of connected sections constituting the back of the boiler and forming flues communicating with the smoke outlet of the boiler; the sections interposed between the series of sections constituting the front of said combustion chamber and the series of sections constituting the back of the boiler forming flues between said combustion chamber and the series of sections constituting the back of the boiler, and a plurality of members arranged end to end in said combustion chamber comprising a longitudinal chamber provided at its ends with air inlets and relatively narrow portions extending therefrom; said members jointly forming a continuous duct for conducting secondary air to the base of said combustion chamber.
40. 8. A boiler of the character described comprising front, rear and intermediate series of connected sections forming a fuel receptacle and a combustion chamber, a series of connected back sections, registering ribs on said back sections extending rearwardly and upwardly from the lower front corners thereof forming flue members communicating with a smoke outlet, and registering ribs on a said series of connected sections interposed between said fuel receptacle and said back sections; the registering ribs on said interposed sections extending downwardly and inwardly from the upper rear corners thereof, and forming flue members cooperating with the flue members of said

- back sections to form continuous passages extending from said fuel receptacle to said smoke outlet, substantially as specified.
9. A boiler of the character described comprising end sections, and a plurality of transverse members each composed of a series of connected sections, certain of said members jointly constituting a fuel receptacle having inlet and outlet openings, and one of said members in conjunction with other of the remaining members forming a combustion chamber communicating with said fuel receptacle, and having flues therein communicating with said combustion chamber, and a further member constituting the back of the boiler having an inlet and an outlet and forming flues connecting said first-named flues with said last-named outlet, substantially as specified.
10. A boiler of the character described comprising end sections, and a plurality of transverse members each composed of a series of connected sections, certain of said members jointly constituting a fuel receptacle having inlet and outlet openings and one of said members in conjunction with other of the remaining members forming a combustion chamber communicating adjacent to its base with said fuel receptacle, and having flues therein whose inlet ends communicate with the upper portion of said combustion chamber, and a further member constituting the back of the boiler having a smoke outlet and flues; the inlet ends of said flues communicating with the outlet ends of the flues first-named and forming therewith a series of passages extending from said combustion chamber to said smoke outlet, substantially as specified.
11. A boiler of the character described comprising end sections, and a plurality of transverse members each composed of a series of connected sections, certain of said sections jointly constituting a fuel receptacle having inlet and outlet openings, and one of said members in conjunction with other of the remaining members forming a combustion chamber communicating adjacent to its base with said fuel receptacle, and having flues therein whose inlet ends communicate with the upper portion of said combustion chamber, a secondary air duct arranged in said combustion chamber intermediate the outlet openings of said combustion chamber, and the inlet of the flues formed in the member forming part of said combustion chamber for conducting preheated air to the base of said combustion chamber, and a further member constituting the back of the boiler having a smoke outlet and flues; the inlet ends of said flues communicating with the outlet ends of the flues first-named, and forming therewith a series of passages extending from said combustion chamber to said smoke outlet, substantially as specified.
12. A boiler of the character described comprising a series of end sections and a plurality of transverse members each composed of a plurality of connected sections; two of said members constituting a fuel receptacle having inlet and outlet passages therein, an intermediate member having flues therein; one side of said intermediate member jointly with one of the members constituting said fuel receptacle forming a combustion chamber communicating with said fuel receptacle, and a further member constituting the back of the boiler having a smoke outlet therein and flues; the flues of said further member, in conjunction with the flues of said intermediate member, forming a series of sinuous flues between said combustion chamber and said smoke outlet, substantially as specified.
13. A boiler of the character described comprising a series of end sections and a plurality of transverse members constituting a fuel receptacle having inlet and outlet passages therein, an intermediate member having flues therein; one side of said intermediate member jointly with one of the members constituting said fuel receptacle forming a combustion chamber communicating with said fuel receptacle; the front wall of said intermediate member comprising an unbroken lower portion and an apertured upper portion communicating with the flues therein, a longitudinal projection on said front wall, between said unbroken and said apertured portions, having a recess therein, an air duct having an enlarged upper portion and a relatively narrow outlet portion extending therefrom, means at the upper end of said duct adapted to engage the recess in said longitudinal projection to support said duct, and a further member constituting the back of the boiler having a smoke outlet therein and flues, the flues of said further member in conjunction with the flues of said intermediate member forming a series of sinuous flues between said combustion chamber and said smoke outlet, substantially as specified.
14. A boiler of the character described comprising a series of end sections and a plurality of transverse members constituting a fuel receptacle having inlet and outlet passages therein, an intermediate member having flues therein; one side of said intermediate member jointly with one of the members constituting said fuel receptacle forming a combustion chamber communicating with said fuel receptacle; the front wall of said intermediate member comprising an unbroken lower portion and an apertured upper portion communicating with the flues therein, a longitudinal projection on said front wall, between said unbroken and said apertured portions, having a recess therein, an air duct having an enlarged upper portion

tion and a relatively narrow outlet portion extending therefrom, lugs at the upper ends of said duct adapted to engage the recess in said longitudinal projection to support said duct, and a further member constituting the back of the boiler having a smoke outlet therein and flues; the flues of said further member in conjunction with the flues of said intermediate member forming a series of sinuous flues between said combustion chamber and said smoke outlet, substantially as specified.

15. A boiler of the character described comprising a series of end sections and a plurality of transverse members constituting a fuel receptacle having inlet and outlet passages therein, an intermediate member having flues therein; one side of said intermediate member jointly with one of the members constituting said fuel receptacle forming a combustion chamber communicating with said fuel receptacle; the front wall of said intermediate member comprising an unbroken lower portion and an apertured upper portion communicating with the flues

therein, a longitudinal projection on said front wall, between said unbroken and said apertured portions, having a recess therein, an air duct composed of a plurality of vertical sections arranged end to end and forming an enlarged upper portion communicating with a source of air supply, and relatively narrow outlet portions extending from said enlarged upper portions, and hook members at the upper ends of said duct sections adapted to engage with the recess in said longitudinal projection to support said duct sections; and a further member constituting the back of the boiler having a smoke outlet therein and flues; the flues of said further member, in conjunction with the flues of said intermediate member, forming a series of sinuous flues between said combustion chamber and said smoke outlet, substantially as specified.

Signed at the city of Buffalo, Erie County, in the State of New York, this 23d day of November, one thousand nine hundred and twenty.

FRANK B. HOWELL.
